Primary Examiner—Celia Murphy

(74) Attorney, Agent, or Firm—Richard B. Klar, Esq.

(57) CLAIM

I claim the ornamental design for a buttocks support device, as shown and described.

DESCRIPTION

FIG. 1 is a rear perspective view showing the invention; the broken lines are intended to represent a human body and attachment and adjustment means and art not intended to be part of the invention and the invention is not limited to any particular means;

FIG. 2 is a front perspective view; and,

FIG. 3 is a side view.

1 Claim, 2 Drawing SheetsFIG. 1
